*Fig. 3**To all whom it may concern:*

Be it known that we, Arthur W. Seyfried and Peter W. Lahr, citizens of the United States, residing at Racine, State of Wisconsin, have invented a new, original, and ornamental Design for a Multiple Spindle Drink Mixer, of which the following is a specification, reference being had to the accompanying drawings, forming a part hereof.

Fig. 1 is a front elevational view of a multiple spindle drink mixer embodying our new design.

Fig. 2 is a side elevational view of the same.

Fig. 3 is a rear elevational view of the mixer.

Fig. 4 is a top plan view.

Fig. 5 is a horizontal sectional view in the plane of the line 5—5 of Fig. 1.

We claim:

The ornamental design for a multiple spindle drink mixer, as shown.
